UNITED STATES PATENT OFFICE.

LOUIS ABRAMOVITZ, OF NEW YORK, N. Y.

FAUCET.

1,675,999.

Specification of Letters Patent. Patented Oct. 14, 1913.

Application filed March 11, 1913. Serial No. 753,546.

To all whom it may concern:

Be it known that I, LOUIS ABRAMOVITZ, a citizen of the United States, residing in New York city, county and State of New York, have invented certain new and useful Improvements in Faucets, of which the following is such a full, clear, and exact description as will enable any one skilled in the art to which it appertains to make and use the same, reference being had to the accompanying drawings, forming part of this specification.

My invention relates to an improved faucet for controlling the delivery of liquids, and the objects of the invention are to provide a triple-action faucet by means of which liquids of two different characters may each be delivered at will in its pure state, or a mixture of these two liquids may be delivered at will.

A further object of the invention is to vary the proportion at will of the liquids when mixed together and delivered from the faucet.

With these and other objects in view my invention consists in the various novel and peculiar arrangements and combinations of the several parts of the device, all as hereinafter fully set forth and then pointed out in the claims.

I have illustrated a type of my invention in the accompanying drawings, wherein:

Figure 1 is a vertical central sectional view of my improved faucet, the valve of which is shown as having its port, which is common to the two supply pipes, registering with the same to deliver a mixture of the liquids. Fig. 2 is a top plan view of the device shown in Fig. 1. Fig. 3 is a horizontal sectional view of part of the device the plane of which is indicated by the line 3—3 in Fig. 1. Fig. 4 is a horizontal sectional view of part of the device the plane of which is indicated by the line 4—4 in Fig. 1. Fig. 5 is a side elevation of the valve shown as detached. Fig. 6 is a similar view of the valve. Fig. 7 is a central vertical sectional view of the upper portion of a modified form of the valve. Fig. 8 is a diagrammatic view showing how the proportions of the two liquids may be varied in relation to each other in forming the mixture.

Referring to the drawings in which like numbers of reference designate like parts throughout, 1 indicates a faucet having valve casing 2, in which is mounted a hollow plug

valve 3, which tapers downwardly toward its lower end where it is open at 4 and where it discharges into the spout 5, of the faucet. The upper and closed end of the plug valve 3, is provided with a stem 6, which passes through a screw-cap 7, secured upon the upper end of the valve casing 2, and between this cap and the upper end of the valve is placed a spring 8, for keeping the valve firmly set in its tapering seat in the valve casing. The valve casing is provided with a lateral extension 9, through which passes two supply-ducts 10 and 11, which in the present instance are arranged in the same vertical plane and are of the same diameter. The two ducts 10 and 11 have their outer ends opening as supply ports into the valve casing 2, and the plug valve 3, is provided with two similar passages or inlet ports 12 and 13, located one above the other and adapted to register with the upper and lower supply ducts 10 and 11, respectively, but not to so register at the same time; that is to say, when the port 12, registers with the supply duct 10, the port 13, is closed in respect to the supply duct 11, and vice versa. The plug valve 3, is also provided with a third passage or inlet port 14, which is sufficiently large to register with both the supply ducts 10 and 11 simultaneously, and at which time the other two ports 12 and 13 are closed in respect to the supplies.

The plug valve 3 is provided at a suitable point on its head with a pin 16, which is in range of a similar pin 15, located on the valve casing so that the valve may be turned almost through a full circle in one direction, and then turned back a similar distance in the other direction, though, of course, these pins may be omitted and the valve be capable of turning without limit.

The lateral extension 9, of the faucet is closed at 17 at its end and it is provided with a screw-thread 18 for screwing into a fitting 19, which is provided at two diametrically opposite points with threaded bosses or projections 20 and 21, respectively, which receive the threaded ends of the liquid supply pipes 22 and 23, respectively. The liquid supply pipe 22, communicates with the supply duct 10, of the faucet through a lateral perforation 24 in the extension 9, and the pipe 23, communicates with the supply duct 11, through a lateral perforation 25, likewise formed in the extension 9. The fitting 19, as well as the con-

nected liquid supply pipes 22 and 23, respectively, are mounted in a stationary part indicated at 26, such as an ordinary wall or partition, and the extension 9, is provided with a flange 27, which surrounds the extension and lies flatly against the wall 26, when the parts are in position.

Assuming that the pipe 22, supplies cold water the course of which is indicated by the arrow marked "C", and that the pipe 23 supplies hot water, as indicated by the arrow marked "H", to the respective supply ducts 10 and 11, Fig. 1 shows the valve adjusted in such position that its mixing port 14, is open alike to both the cold and hot supplies 10 and 11, and under this condition each of these liquids is discharged alike into the hollow interior of the plug valve 3, and passes thence through the bottom into the spout 5, and out of the same, thereby delivering from the faucet a mixture of hot and cold liquid, or one that is tepid. The mixing port 14 of the valve is so constructed by being slot-shaped and disposed diagonally instead of vertically in the wall of the plug valve, that it may be made to readily vary the proportion between the amount of cold and hot liquid admitted through the valve. This regulation of the proportions of the two liquids is shown diagrammatically in Fig. 8, in which the mixing port is indicated at the left hand as uncovering the whole of the hot liquid supply 11, but only partially uncovering the cold liquid supply 10, thereby giving a greater proportion of the hot liquid in the mixture. At the right hand of Fig. 8 the reverse of this condition is indicated. By shifting the valve slightly in one direction or the other from the two positions indicated in the diagram in Fig. 8, other variations may be made in the proportions of the liquids thus mixed together.

In Fig. 7 I show a modification in which the mixing port 14 of the plug valve is arranged in vertical position in the periphery of the valve instead of obliquely, as in the other form. This arrangement uncovers simultaneously and completely both the cold and hot supplies 10 and 11.

I provide the valve stem 6 with a handle 29, having four equidistant arms 30, 31, 32 and 33, respectively, the ends of which are shaped so as to receive a suitable inscription or label reading "Closed", "Cold", "Hot", "H & C", respectively, as indicated in Fig. 2. These four arms are so related to the location of the inlet ports 12, 13 and 14, of the plug valve, that when the valve is adjusted to open both of the supplies 10 and 11 by means of the mixing port 14, and thereby deliver from the faucet hot and cold or tepid liquid, the arm bearing the hot and cold label points forwardly in the direction 65 of the spout 5 of the faucet. Similarly when

the valve port 12 registers with the cold liquid supply 10, the arm bearing the word "Cold," is in a position directly above the spout 5, of the faucet, and in the same way the arm marked "Hot" comes in position 70 over the spout 5 of the faucet, and the arm marked "Closed" comes in such position when the faucet is operating under either of these conditions.

In using my improved faucet with the ordinary hot and cold water supplies in a building it will be seen that my faucet reduces the number of such devices by one-half. This faucet also saves a considerable quantity of hot water in some cases, for example, where it is customary to draw a vessel full of hot water, such water is often too hot when drawn from the ordinary faucet and some of it is thrown away and cold water substituted for the part thus thrown away in order to get a lower temperature. With my faucet the temperature of the water is regulated by adjusting the valve as described so that the faucet itself delivers the water at practically the desired 90 temperature.

It will thus be observed that my faucet is particularly well adapted for use with a kitchen sink, as the cup-shaped fitting to which the two supply pipes are connected 95 at opposite points on the circumference thereof, is internally screw-threaded and receives the externally screw-threaded extension of the faucet which contains the two supply ducts. This requires but a single opening in the wall or part on which the faucet is mounted and permits its being readily removed whenever occasion requires. Furthermore, the turning of the valve being limited to substantially a full circle either 100 in the direction of the movement of the hands of a clock, or in the reverse direction, the stop-device which thus limits the movement is herein shown as so arranged that when the valve is adjusted in "closed" position, (that is with the handle marked "Closed" pointing outwardly over the spout of the faucet), a quarter turn in the direction in which the hands of a clock move will open the mixing-port; another quarter 110 turn in the same direction will open the hot-supply, and a third quarter turn in the same direction will open the cold supply, when the movement in this direction will be checked. By reversing the movement of the 115 valve a quarter turn the hot supply will be opened; by another quarter turn the mixed supply will be opened, and by a third quarter turn the valve may be brought into closed position.

I wish to be understood as not limiting my invention to the exact construction of the several different parts of the device herein shown, as it is manifest that various modifications may be made in such parts without

however, departing from the spirit of my invention.

Having thus described my invention, what I claim and desire to secure by Letters Patent is:

1. A faucet comprising two independent supply-ducts arranged in superposed relation and provided with a rotary plug-valve having three separated inlet ports one of which is adapted to communicate with one of said supply-ducts while the other is closed, and another with the other of said supply-ducts while the first mentioned supply-duct is closed, and the third valve-port being elongated with its central line of length arranged obliquely to the vertical and adapted to register with both of said supply-ducts simultaneously and to open both of them equally when the valve is turned in either direction and also to vary the uncovered area of the openings relatively to each other when turned in either direction, substantially as and for the purpose set forth.
2. A faucet comprising a valve-casing provided with an externally threaded lateral extension having two supply ducts communicating with the valve-chamber and the exterior of the side of said extension, an internally threaded cup-shaped fitting mount-

ed on said lateral extension and provided with laterally projecting nipples registering with the respective supply duct openings in the side of said extension, and the valve provided with ports for coöperating with said two supply ducts, substantially as described.

3. A faucet comprising a valve-casing provided with an externally threaded lateral extension having two supply ducts arranged one above the other in the same vertical plane and communicating with the valve-chamber and the exterior of the side of said extension and closed at the outer ends, an internally threaded cup-shaped fitting mounted on said lateral extension and provided with laterally projecting-nipples registering with the respective supply duct openings in the side of said extension, and the valve provided with ports for coöperating with said two supply-ducts, substantially as described.

In testimony whereof, I have hereunto set my hand in the presence of the two subscribing witnesses.

LOUIS ABRAMOVITZ.
